(57) **CLAIM**

The ornamental design for a medical syringe, as shown and described.

DESCRIPTION

FIG. 1 is a front right perspective view of a medical syringe showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines of even length shown in the drawings illustrate portions of the medical syringe that form no part of the claimed design.
